Fig. 7

FIG. 1 is a perspective view of a snowmobile protective cover embodying my new design.

FIG. 2 is a side elevation view thereof with the cover opened.

FIG. 3 is a side elevational view thereof with the cover closed.

FIG. 4 is a top plan view thereof taken along the lines 4-4 in FIG. 3.

FIG. 5 is a side elevational view thereof taken along the lines 5-5 in FIG. 4.

FIG. 6 is a front elevational view thereof taken along the lines 6-6 in FIG. 4.

FIG. 7 is a side elevational view of a snowmobile protective cover showing a second embodiment of my new design with the cover open, it being understood that the top, rear, and front are identical to those shown in FIGS. 4, 5, and 6.

The broken lines in FIG. 1 are for illustrative purposes only.

The undisclosed sides are substantially mirror images of the sides shown in FIGS. 2 and 7.

I claim:

The ornamental design for a snowmobile protective cover, as shown and described.
